United States Patent Office.

W. C. SCOTT, OF RICHMOND, INDIANA.

Letters Patent No. 90,027, dated May 11, 1869.

IMPROVEMENT IN LUMBER-DRIERS.

The Schedule referred to in these Letters Patent and making part of the same.

To all whom it may concern:

Be it known that I, W. C. SCOTT, of the city of Richmond, and State of Indiana, have invented a new and useful Improvement in Lumber-Kilns; and I do hereby declare that the following is a full, clear, and exact description thereof, reference being had to the accompanying drawings, making a part of this specification, in which—

Figure 1 is a perspective view, showing the interior of the building, and

Figure 2 is an end elevation.

The same letters in the different figures relate to corresponding parts of the kiln.

My invention relates to a kiln, or drying-house for lumber, in which is placed suitable apparatus, consisting of a furnace, with a considerable length of pipe leading from the same, and arranged horizontally in the lower part of the building, through which the products of combustion pass; also tanks containing water, through one of which the products of combustion are passed, for the double purpose of arresting sparks and carrying moisture from the water in the tank, which is discharged into the building with the products of combustion, by which the lumber is kept moist or steamed during the process of drying.

The object of discharging the products of combustion in the building, is to more completely utilize the heat, and at the same time hydrate the air of the kiln by means of the tank, as before stated.

An important feature in my invention consists in the use of the pipes (arranged as above described) for the purpose of radiating, and thus utilizing a greater proportion of heat than would otherwise be the case.

Another important object in the use of the pipes, is to increase the draught of air through the building, which air is heated by the pipes, and passes through the lumber, thus facilitating the drying of the latter.

Suitable openings are made in the lower part of the building, for the admission of air.

To enable others skilled in the art to make and use my invention, I will proceed to describe its construction and operation.

A represents a suitable building, in which the drying-apparatus is placed.

a is the furnace, from which the products of combustion pass through pipe b into tank c, and from the latter, through pipe b', into a receptacle, d, from which they escape into the building.

The twofold purpose of tank c is to arrest and extinguish sparks, and to supply moisture for steaming the lumber.

The object of receptacle d is also to extinguish sparks, should any escape from tank c and reach that point through the pipe.

Tank c is supplied with water, the height of which is always less than the height of the ends of pipes b and b'.

Moisture from the evaporation of the water in tank

c, serves to arrest and extinguish the sparks from the furnace.

The different directions of the discharge and escape of the products of combustion, in passing through tank c, also aid in arresting and extinguishing the sparks in said tank.

The receptacle d is constructed to hold water at the bottom. Its top is a solid plate, e, and its sides, near the top, are perforated or reticulated.

Pipe b' enters receptacle d, and, by means of an elbow, terminates in a vertical position, at a short distance beneath plate e. Thus the products of combustion are discharged against said plate, and escape from the receptacle d into the building, through the perforations or reticulations at the sides of said receptacle, the open capacity of which is equal to or greater than the capacity of pipe b'.

Receptacle d thus effectually destroys any sparks that may escape from tank c, the sparks being precipitated by plate e, and extinguished by the water in the bottom of the receptacle, or prevented by the screen from escaping with the gases.

The lumber to be dried is placed upon the cross-timbers z.

At the commencement of the drying-process, tank c is supplied with the maximum quantity of water, which is evaporated and carried through the pipes to the lumber by the passing currents from the furnace, thus supplying the necessary moisture for steaming the lumber.

The quantity or depth of water in tank c is gradually lowered by evaporation, (and by being drawn off, if necessary,) to proportionately diminish the quantity of moisture conveyed to the lumber as the process of drying advances, thus reducing the water, and stopping the moisture at a proper time to finish drying the lumber.

The water in tank c is not necessarily heated to the boiling-temperature by the passing products of combustion, to insure successful operation of the kiln.

The degree to which the water in said tank is heated depends, to a considerable extent, on the proximity of the surface of the water to the end of pipe b', through which the products of combustion are discharged into the tank.

The evaporation of the water in tank c is sufficient, however, to supply the necessary moisture to the lumber, to promote the process of drying to the best advantage, by preventing the sap from becoming coagulated, or the surface of the lumber from becoming hardened before the interior is properly dried.

A ceiling or floor, u, is located in the upper part of the building, and is provided with apertures n at each corner, through which apertures the gases escape to the chimney, by which the upward draught is equalized throughout the interior of the building, and the heat thus more equally diffused through the lumber.

J and J' are air-ducts, admitting sufficient air to the

interior of the building to supply the partial vacuum produced by the heat from the furnace, thus increasing the volume of heated gases, and facilitating the drying-process.

I represents a pipe for admitting cold air into the top of tank *c*, to aid in precipitating the sparks, and also to increase the quantity of gases discharged in the building.

t is a feed-pipe, through which water is supplied to receptacle *d*.

r, fig. 2, shows a feeder on the outside of the building, by which tank *c* is supplied with water, the top of feeder *r* being lower than the ends of pipes *b* and *b'*, thus preventing the tank from being supplied with sufficient water to reach and interfere with the ends of said pipes.

At *v*, fig. 2, are air-passages, by which air is admitted beneath the furnace, entering the latter near the rear end, by which the heat radiated beneath the furnace is economized, and the combustion increased.

s is a slide for closing the air-passages *v*, when desired.

g represents a damper, for regulating the draught through the building, and is operated by means of a pulley with a cord suspended.

The pipes *b* and *b'*, through which the products of combustion pass, are intended (besides the purposes aforementioned) to radiate the heat in the lower part of the building, the entire length of pipe between the furnace and the point at which the products of combustion are discharged into the building being such as will radiate the most heat without destroying a proper draught from the furnace.

Having thus fully described my said invention, What I claim, and desire to secure by Letters Patent, is—

With the building and furnace, the heat-radiating pipes, arranged in combination with tank *c* and receptacle *d*, in the manner and for the purpose set forth.

Also, the tank *c*, for the purpose of extinguishing sparks and supplying moisture to the lumber, as set forth.

Also, the receptacle *d*, with its top plate *e*, and perforated or reticulated sides, when arranged, with relation to pipe *b*, in the manner set forth.

W. C. SCOTT.
